MODEL RACING CAR

Anthony Colin Bruce Chapman, Norfolk, England, assignor to Lotus Components Limited, Norwich, Norfolk, England

Filed Nov. 5, 1970, Ser. No. 25,847

Claims priority, application Great Britain May 9, 1970

Term of patent 7 years

Int. Cl. D21—01

U.S. Cl. D34—15

FIG. 1 is a top plan view of the model racing car showing my new design; and

FIG. 2 is a front elevational view thereof; and

FIG. 3 is a left side elevational view, the right side being substantially a mirror image thereof; and

FIG. 4 is a rear elevational view thereof.

I claim:

The ornamental design for a model racing car, as shown and described.
